(57) **ABSTRACT**

For use in a system having a master device and slave devices (e.g., an electronic blasting system) and utilizing an automatic detection process that causes any slave devices that have not previously been identified to the master device to identify themselves to the master device, an enhancement to the detection process employs at least a second discriminator to detect superimposed responses from simultaneously responding slave devices, and a “deconvolution” algorithm in order to ascertain their identities.

**ENHANCED METHOD, DEVICE, AND
SYSTEM FOR IDENTIFYING AN UNKNOWN
OR UNMARKED SLAVE DEVICE SUCH AS IN
AN ELECTRONIC BLASTING SYSTEM**

RELATED APPLICATIONS

This application is a continuation-in-part of application Ser. No. 11/339,159 entitled "Multiple Slave Logging Device," filed Jan. 24, 2006 now U.S. Pat. No. 7,617,775, which was a continuation-in-part of application Ser. No. 10/736,166 entitled "Dynamic Baseline in Current Modulation-Based Communication," filed Dec. 13, 2003 and issued as U.S. Pat. No. 6,988,449 on Jan. 24, 2006, which was in turn a continuation-in-part of application Ser. No. 10/619,687 entitled "Current Modulation-Based Communication," filed Jul. 15, 2003 and issued as U.S. Pat. No. 6,966,262 on Nov. 22, 2005.

BACKGROUND OF THE INVENTION

The present invention is directed generally to systems comprising master and slave devices, and more particularly to a method of identifying an unknown or unmarked slave device in the system such as in an electronic blasting system.

SUMMARY OF THE INVENTION

In a system having a master device and slave devices (e.g., an electronic blasting system), an "autobus detection" command has been utilized by the master device to cause any slave devices that have not been identified to the master device previously to respond with information identifying the slave device. As the number of unidentified slave devices connected to the system increases, however, the likelihood increases that two or more slave devices will respond simultaneously to such a command and remain undistinguishable to the master device. In an embodiment of the present invention, the detection process is enhanced by employing at least a second discriminator to detect such superimposed responses, and a "deconvolution" algorithm in order to ascertain the identities of simultaneously responding slave devices. This enhancement provides a robustness that, for example, can permit a user to connect to the system a whole array of slave devices "off-the-shelf" without having to first identify the slave devices in a time-consuming, one-by-one process.

BRIEF DESCRIPTION OF THE DRAWINGS

FIG. 1 is an overall view showing a layout of an electronic blasting system in which the present invention may be employed.

FIG. 2 is an overall view showing a layout of an alternate configuration of such an electronic blasting system.

FIG. 3 is a sectional view of a preferred detonator that may be used in the electronic blasting system of FIGS. 1 & 2.

FIG. 4 is a schematic representation of the major electrical aspects of the electronic ignition module (EIM) of the detonator of FIG. 3, including an application-specific integrated circuit (ASIC).

FIG. 5 is a schematic representation of a preferred circuit design for the ASIC of FIG. 4.

FIG. 6a is a graph of voltage versus time illustrating a preferred voltage modulation-based communication from a blasting machine to detonator(s) in the electronic blasting system of FIGS. 1 & 2.

2

FIG. 6b is a graph of voltage versus time illustrating a preferred voltage modulation-based communication from a logger to detonator(s) the electronic blasting system of FIGS. 1 & 2.

5 FIG. 7a is a graph of current versus time illustrating a preferred current modulation-based response back from a detonator to a blasting machine the electronic blasting system of FIGS. 1 & 2.

10 FIG. 7b is a graph of current versus time illustrating a preferred current modulation-based response back from a detonator(s) to a logger the electronic blasting system of FIGS. 1 & 2.

15 FIG. 8 is a graph illustrating communication to a detonator and response back from the detonator to any response-eliciting command other than an Auto Bus Detection command.

FIG. 9 is a graph showing communication to, and response back from, a detonator in response to an AutoBus Detection command.

20 FIGS. 10a, 10b, 10c, and 10d are a flowchart illustrating a preferred logic sequence for the operation of an electronic blasting system of FIGS. 1 & 2.

FIG. 11 is a flowchart illustrating a preferred logic sequence for the operation of a detonator that may be used in the electronic blasting system of FIGS. 1 & 2, beginning with 25 the reception by the detonator of a Fire command.

FIG. 12 is a graph of voltage and current versus time in a firing capacitor in a detonator such as that of FIG. 3, showing a constant-current, rail-voltage regulated charging process.

30 FIG. 13a shows ideal, noise-free current-based "talkback" similar to FIG. 7a.

FIG. 13b shows "ramped" talkback such as may be caused by environmental noise encountered in the use of a blasting system.

35 FIG. 13c shows irregular talkback such as may be caused by environmental noise.

FIGS. 13d and 13e show field traces of irregular talkback.

FIG. 14 is a block diagram of a multiple slave logger.

40 FIG. 15 is a graph showing two detonators responding simultaneously to a detection command issued by the master device.

FIG. 16 is a circuit diagram showing two discriminators in the master device.

DETAILED DESCRIPTION OF A PREFERRED EMBODIMENT

To describe the present invention with reference to the details of a particular preferred embodiment, it is noted that 50 the present invention may be employed in an electronic system comprising a network of slave devices, for example, an electronic blasting system in which the slave devices are electronic detonators. As depicted in FIG. 1, one embodiment of such an electronic blasting system may comprise a number 55 of detonators 20, a two-line bus 18, leg wires 19 including connectors for attaching the detonator to the bus 18, a logger (not shown), and a blasting machine 40. The detonators 20 are preferably connected to the blasting machine 40 in parallel (as in FIG. 1) or in other arrangements including branch (as in 60 FIG. 2), tree, star, or multiple parallel connections. A preferred embodiment of such an electronic blasting system is described below, although it will be readily appreciated by one of ordinary skill in the art that other systems or devices could also be used, and many configurations, variations, and 65 modifications of even the particular system described here could be made, without departing from the spirit and scope of the present invention.

The blasting machine 40 and logger may preferably each have a pair of terminals capable of receiving bare copper (bus) wire up to, for example, 14-gauge. The logger's terminals may also preferably be configured to receive steel detonator wires (polarity insensitive), and the logger should have an interface suitable for connecting to the blasting machine 40. The blasting machine 40 and logger are preferably capable of being operated by a person wearing typical clothing used in mining and blasting operations, e.g., thick gloves. The blasting machine 40 and logger may preferably be portable handheld battery-powered devices that require password entry to permit operation and have illuminated displays providing menus, instructions, keystroke reproduction, and messages (including error messages) as appropriate. The blasting machine 40 may preferably have a hinged lid and controls and indicators that include a lock for the power-on key, a numeric keypad with up/down arrows and "enter" button, a display, an arming button, an indicator light(s), and a firing button.

The blasting machine 40 and logger should be designed for reliable operation in the anticipated range of operating temperatures and endurance of anticipated storage temperatures and are preferably resistant to ammonium nitrate and commonly-used emulsion explosives. The blasting machine 40 and logger are also preferably robust enough to withstand typical treatment in a mining or blasting environment such as being dropped and trodden on, and may thus have casings that are rugged, water and corrosion-resistant and environmentally sealed to operate in most weather. The blasting machine 40 and logger should, as appropriate, meet applicable requirements of CEN document prCEN/TS 13763-27 (NMP 898/FABERG N 0090 D/E) E 2002-06-19 and governmental and industry requirements. To the extent practical, the logger is preferably designed to be incapable of firing any known electric and electronic detonators and the blasting machine 40 to be incapable of firing all known electric detonators and any other known electronic detonators that are not designed for use with the blasting machine 40. An initial electrical test of the system to detect such a device can be employed to provide further assurance that unintended detonators are not fired.

The bus 18 may be a duplex or twisted pair and should be chosen to have a pre-selected resistance (e.g., in the embodiment described here, preferably 30 to 75 Ω per single conductor). The end of the bus 18 should not be shunted, but its wire insulation should be sufficiently robust to ensure that leakage to ground, stray capacitance, and stray inductance are minimized (e.g., in the embodiment described herein, preferably less than 100 mA leakage for the whole bus, 50 pF/m conductor-to-conductor stray capacitance, and 1 μ H/m conductor-to-conductor stray inductance) under all encountered field conditions.

The leg wires 19 and contacts should be chosen to have a pre-selected resistance measured from the detonator terminal to the detonator-to-bus connector (e.g., in the embodiment described here, 50 to 100 Ω per single conductor plus 25 m Ω per connector contact). It will be recognized that the particular detonator-to-bus connector that is used may constrain the choice of bus wire. From a functional standpoint, the detonators 20 may be attached at any point on the bus 18, although they must of course be a safe distance from the blasting machine 40.

As shown in FIG. 3, a suitable detonator 20 for use in an electronic blasting system such as that described here may comprise an electronic ignition module (EIM) 23, a shell 29, a charge 36 (preferably comprising a primary charge and base charge), leg wires 19, and an end plug 34 that may be crimped in the open end of the shell 29. The EIM 23 is preferably programmable and includes an igniter 28 and a circuit board

to which may be connected various electronic components. In the embodiment described here, the igniter 28 is preferably a hermetically sealed device that includes a glass-to-metal seal and a bridgewire 27 designed to reliably ignite a charge contained within the igniter 28 upon the passage through the bridgewire 27 of electricity at a predetermined "all-fire" voltage level. The EIM 23 (including its electronics and part or all of its igniter 28) may preferably be insert-molded into an encapsulation 31 to form a single assembly with terminals for attachment of the leg wires 19. Assignee's co-pending U.S. patent application Ser. No. 10/158,317 (at pages 5-8 and FIGS. 1-5) and Ser. No. 10/158,318 (at pages 3-8 and FIGS. 1-6), both filed on May 29, 2002, are hereby incorporated by reference for their applicable teachings of the construction of such detonators beyond the description that is set forth herein. As taught in those applications, an EIM 23 generally like the one depicted in FIG. 3 can be manufactured and handled in standalone form, for later incorporation by a user into the user's own custom detonator assembly (including a shell 29 and charge 36).

The circuit board of the EIM 23 is preferably a microcontroller or programmable logic device or most preferably an application-specific integrated circuit chip (ASIC) 30, a filtering capacitor 24, a storage capacitor 25 preferably, e.g., 3.3 to 10 μ F (to hold a charge and power the EIM 23 when the detonator 20 is responding back to a master device as discussed further below), a firing capacitor 26 (preferably, e.g., 47 to 374 μ F) (to hold an energy reserve that is used to fire the detonator 20), additional electronic components, and contact pads 22 for connection to the leg wires 19 and the igniter 28. A shell ground connector 32 protruding through the encapsulation 31 for contact with the shell 29 and connected to, e.g., a metal can pin on the ASIC 30 (described below), which is connected to circuitry within the ASIC 30 (e.g., an integrated silicon controlled resistor or a diode) that can provide protection against electrostatic discharge and radio frequency and electromagnetic radiation that could otherwise cause damage and/or malfunctioning.

Referring to FIG. 4, a preferred electronic schematic layout 40 of a detonator 20 such as that of FIG. 3 is shown. The ASIC 30 is preferably a mixed signal chip with dimensions of 3 to 6 mm. Pins 1 and 2 of the depicted ASIC 30 are inputs to the leg wires 19 and thus the bus 18, pin 3 is for connection to the shell ground connector 32 and thus the shell 29, pin 6 is connected to the firing capacitor 26 and bridgewire 27, pin 7 is connected to the filtering capacitor 24, pin 10 is connected to the bridgewire 27, pin 13 is grounded, and pin 14 is connected to the storage capacitor 25.

Referring specifically now to FIG. 5, the ASIC 30 may 50 preferably consist of the following modules: polarity correct, communications interface, EEPROM, digital logic core, reference generator, bridge capacitor control, level detectors, and bridgewire FET. As shown, the polarity correct module may employ polarity-insensitive rectifier diodes to transform 55 the incoming voltage (regardless of its polarity) into a voltage with common ground to the rest of the circuitry of the ASIC 30. The communication interface preferably shifts down the voltages as received from the blasting machine 40 so that they are compatible with the digital core of the ASIC 30, and also 60 toggles and transmits the talkback current (described below) to the rectifier bridge (and the system bus lines) based on the output from the digital core. The EEPROM module preferably stores the unique serial identification, delay time, hole registers and various analog trim values of the ASIC 30. The 65 digital logic core preferably holds the state machine, which processes the data incoming from the blasting machine 40 and outgoing talkback via the communication interface. Ref-

erence generators preferably provide the regulated voltages needed to power up the digital core and oscillator (e.g., 3.3V) and also the analog portions to charge the firing capacitor **26** and discharge the firing MOSFET. The bridge capacitor control preferably contains a constant current generator to charge up the firing capacitor **26** and also a MOSFET to discharge the firing capacitor **26** when so desired. The level detectors are preferably connected to the firing capacitor **26** to determine based on its voltage whether it is in a charged or discharged state. Finally, the bridgewire MOSFET preferably allows the passage of charge or current from the firing capacitor **26** across the bridgewire **27** upon actuation by pulling to ground.

Communication Protocol

Communication of data in a system such as shown in FIGS. **1** and **2** may preferably consist of a 2-wire bus polarity independent serial protocol between the detonators **20** and a logger or blasting machine **40**. Communications from the blasting machine **40** may either be in individual mode (directed to a particular detonator **20** only) or broadcast mode where all the detonators **20** will receive the same command (usually charging and fire commands). The communication protocol is preferably serial, contains cyclic redundancy error checking (CRC), and synchronization bits for timing accuracy among the detonators **20**. There is also a command for the auto-detection of detonators **20** on the bus **18** that otherwise had not been entered into the blasting machine **40**.

When the blasting machine **40** and detonators **20** are connected, the system idle state voltage is preferably set at $V_{B,H}$. The slave detonators **20** then preferably obtain their power from the bus **18** during the high state, which powers up their storage capacitors **25**. Communications from the blasting machine **40** or logger to the ASICs **30** is based on voltage modulation pulsed at the appropriate baud rate, which the ASICs **30** decipher into the associated data packets.

As shown in FIGS. **6a** and **6b**, different operating voltages $V_{L,L}$ and $V_{L,H}$ can be used by the logger versus those of the blasting machine **40**, $V_{B,L}$ and $V_{B,H}$. In the embodiment described here, suitable values for $V_{L,L}$ and $V_{L,H}$ are 1 to 3V and 5.5 to 14V, respectively, while suitable values for $V_{B,L}$ and $V_{B,H}$ are 0 to 15V and 28V or higher, respectively. Further, a detonator **20** in such a system may preferably utilize this difference to sense whether it is connected to the blasting machine **40** or logger (i.e., whether it is in logger or blaster mode), such as by going into logger mode when the voltage is less than a certain value (e.g., 15V) and blaster mode when it is above another value (e.g., 17V). This differentiation permits the ASIC **30** of the detonator **20** to, when in logger mode, preferably switch on a MOSFET to discharge the firing capacitor **26** and/or disable its charging and/or firing logic. The differentiation by the detonator **20** is also advantageously simplified if there is no overlap between the high/low ranges of the blasting machine **40** and the logger, as shown in FIGS. **6a** and **6b**. (Each of these figures depicts nominal values for high and low, but it is further preferable that the maximum and minimum acceptable values for the highs and lows also do not permit overlap).

On the other hand, instead of voltage modulation, the communication from the ASICs **30** to the blasting machine **40** or logger is based on current modulation ("current talkback"), as shown in FIGS. **7a** and **7b**. With current modulation, the ASICs **30** toggle the amount of current to the logger (between $I_{L,L}$, preferably 0 mA, and $I_{L,H}$, preferably a value that is at least 0.1 mA but substantially less than $I_{B,H}$) or blasting machine **40** (between $I_{B,L}$, preferably 0 mA, and $I_{B,H}$, preferably a value that is at least 5 mA but not so high as to possibly overload the system when multiple detonators **20** respond),

which then senses and deciphers these current pulse packets into the associated data sent. The toggling of current by an ASIC **30** can be suitably achieved by various known methods such as modulating the voltage on a sense resistor, a current feedback loop on an op amp, or incorporating constant current sinks, e.g., a current mirror. This current talkback from the detonators back to the master can be performed when the voltage of the bus **18** is high or low, but if performed when the bus **18** is high, the other ASICs **30** are continuously replenishing the storage capacitors **25**, causing a high background current draw (especially when many detonators **20** are connected to the bus **18**). The current talkback thus is preferably conducted when the bus **18** is held low and the rectifier bridge diodes in a communication interface of the detonators are reverse-biased (whereas they are forward biased when the bus is held high) so the ASICs **30** draw operating current from the storage capacitors **25** rather than the bus **18**, reducing background current noise and improving the signal-to-noise ratio of the sensed talkback current at the blasting machine **40** or logger. Alternately, talkback could be performed with the bus held high if the system and detonators are configured and/or programmed so that the detonators do not perform any other tasks that could cause an undesirable level of background noise during talkback by any detonator.

Preferably with the bus voltage held low, "dynamic baselining" of the current talkback can also be utilized, and is preferable. As shown in FIG. **13a**, with noise-free current talkback, the highs ("1's") and lows ("0's") in the talkback conveyed by the detonators are clearly defined, and the discriminator of the blasting machine or logger reliably differentiates their digital levels. As shown in FIGS. **13b-e**, however, under conditions of significant environmental noise such as electrical interference, EMI, EMC, rf, ESD, steady state and dynamic wire leakage, the talkback current may be ramped (with a regularly increasing or decreasing baseline) or irregular such that it may not necessarily always be differentiated properly by the master device. To better preserve communication integrity, the master device therefore preferably measures the "baseline" of the talkback current on a continuous basis and compensates for any variations therein.

As described below, communications both ways between the master device and slave devices may preferably utilize a protocol that includes synchronization bits (preferably four bits, i.e., 0101), both at the beginning of a serial data packet and preferably also between each "word" or "byte" of a packet. The dynamic baselining of the present invention preferably measures the current of the zero bits of these synchronization portions, and establishes the measured value as the baseline for the current of the immediately ensuing portion of talkback. Moreover, this "dynamic baselining" is preferably performed before each word of data or command in the serial packet. Thus, the zero levels may be measured at points such as those labeled "A" and/or "B" in FIGS. **13b** and **13c**, preferably being measured at least on the intermediate synchronization bits that preferably precede each word of data in the serial packet (as explained below) including at point B, so that the baseline is corrected close in time to each incoming word of data.

The dynamic baselining is preferably performed using an algorithm implemented in the master device, for example, through programming the microcontroller or programmable logic devices such as FPGA or CPLD. The zero current level of the synchronization bits may be measured using typical A/D conversion techniques such as A/D converters or comparators.

Serial Data Communication (Serial Data Line) Organization

In communications to and from the master devices and slave devices, the serial data communication interface may preferably comprise a packet consisting of a varying or, more preferably, a fixed number (preferably 10 to 20) of "bytes" or "words" that are each preferably, e.g., twelve bits long, preferably with the most significant bit being sent first. Depending on the application, other suitable sized words could alternately be used, and/or a different number of words could be used within the packet. Also, a different packet structure could alternately be employed for communications from the master device as compared to those of communications from the slave devices.

The first word of the packet of the embodiment described here is preferably an initial synchronization word and can be structured such that its first three bits are zero so that it is effectively received as a nine-bit word (e.g., 101010101, or any other suitable arrangement).

In addition to containing various data as described below, the subsequent words may also preferably each contain a number of bits—for example, four bits at the beginning or end of each word—that are provided to permit mid-stream re-synchronization (resulting in a word structured as 0101_D7: D0 or D7:D0_0101 and thus having eight bits that can be used to convey data, or "data bits"). Preferred schemes of initial synchronization and re-synchronization are described further under the corresponding heading below.

Another word of the packet can be used to communicate commands, such as is described under the corresponding heading below.

Preferably five to eight additional bytes of the packet are used for serial identification (serial ID) to uniquely (as desired) identify each detonator in a system. The data bits of the serial ID data may preferably consist at least in part of data such as revision number, lot number, and wafer number, for traceability purposes. In broadcast commands from the master device, these words do not need to contain a serial ID for a particular detonator and thus may consist of arbitrary values, or of dummy values that could be used for some other purpose.

Additional words of the packet are preferably used to convey delay time information (register) (and comprise enough data bits to specify a suitable range of delay time, e.g., in the context of an electronic blasting system, a maximum delay of on the order of, e.g., a minute) in suitable increments, e.g., 1 ms in the context of an electronic blasting system. (A setting of zero is preferably considered a default error).

In the embodiment described here, one or more additional words of the packet are preferably used for scratch information, which can be used to define blasting hole identifications (hole IDs), with these words comprising enough data bits to accommodate the maximum desired number of hole IDs.

One or more additional words of the packet are preferably used for a cyclic redundancy check (for example, using CRC-8 algorithm based on the polynomial, x^8+x^2+x+1), or less preferably, a parity check, or an error-correction check, e.g., using hamming code. Preferably, neither the initial synchronization word nor the synchronization bits are used in the CRC calculation for either transmission or reception.

Synchronization Word and Re-Synchronization Bits

In the embodiment and application described here, a preferred range of possible communication rates may be 300 to 9600 baud. In a packet sent by the master device, the initial synchronization word is used to determine the speed at which the slave device receives and processes the next word in the packet from the master device; likewise, in a packet sent by

the slave device, the initial synchronization word is used to determine the speed at which the master device receives and processes the next word from the slave device. The first few (enough to obtain relatively accurate synchronization), but not all, of the bits of this initial synchronization word are preferably sampled, in order to permit time for processing and determination of the communication rate prior to receipt of the ensuing word. Synchronization may be effected by, e.g., the use of a counter/timer monitoring transitions in the voltage level—low to high or high to low, and the rates of the sampled bits are preferably averaged together. Throughout transmission of the ensuing words of the packet, i.e., "mid-stream," re-synchronization is then preferably conducted by the receiving device assuming that (e.g., 4-bit) synchronization portions are provided in (preferably each of) those ensuing words. In this way, it can be ensured that synchronization is not lost during the transfer of a packet.

If requested, a slave device responds back, after transmission of a packet from the master device, at the last sampled rate of that packet, which is preferably that of the last word of the packet. (This rate can be viewed as the rate of the initial synchronization word as skewed during the transmission of the packet—in an electronic blasting machine, such skew is generally more pronounced during communication from the detonator to the logger). Referring to FIGS. 8 and 9, communication from a master to a slave device, and a synchronized response back from the slave device, is shown.

As depicted in FIG. 8, the device may preferably be configured and programmed to initiate a response back to individually-addressed commands no later than a predetermined period (after the end trailing edge of the serial input transfer) comprising the time required to complete the input transfer, the serial interface setup for a response back, and the initial portion of the synchronization word (e.g., 000101010101). Preferably the bus 18 should be pulled (and held) low within the capture and processing delay.

Command Word

The data bits of the command word from the master device (e.g., blasting machine or logger) in the serial communication packet may preferably be organized so that one bit is used to indicate (e.g., by being set high) that the master device is communicating, another is used to indicate whether it is requesting a read or a write, another indicates whether the command is a broadcast command or a single device command, and other bits are used to convey the particular command. Similarly, the data bits of the command word from the slave device (e.g., detonator) may preferably be organized so that one bit is used to indicate that the device is responding (e.g., by being set high), another indicates whether a CRC error has occurred, another indicates whether a device error (e.g., charge verify) has occurred, and other bits are discretely used to convey "status flags."

The flag data bits from devices can be used to indicate the current state of the device and are preferably included in all device responses. These flags can be arranged, for example, so that one flag indicates whether or not the device has been detected on the bus, another indicates whether it has been calibrated, another indicates whether it is currently charged, and another indicates whether it has received a Fire command. A flag value of 1 (high) can then signify a response in the affirmative and 0 (low) in the negative.

A preferred set of useful substantive blasting machine/logger commands may include: Unknown Detonator Read Back (of device settings); Single Check Continuity (of detonator bridgewire); Program Delay/Scratch; Auto Bus Detection (detect unidentified devices); Known Detonator Read

Back; Check Continuity (of the detonators' bridgewires); Charge (the firing capacitors); Charge Verify; Calibrate (the ASICs' internal clocks); Calibrate Verify; Fire (initiates sequences leading to firing of the detonators); DisCharge; DisCharge Verify; and, Single DisCharge. As will be explained further below, some of these commands are "broadcast" commands (sent with any arbitrary serial identification and its concomitant proper CRC code) that only elicit a response from any detonator(s) that have not been previously identified or in which an error has occurred, while others are directed to a specific detonator identified by its serial ID. FIGS. 10a-d show a flowchart of a preferred logical sequence of how such commands may be used in the operation of an electronic blasting system, and specific details of the preferred embodiment described here are set forth for each individual command under the Operation headings.

Operation—by Logger

In use, the detonators **20** are preferably first each connected individually to a logger, which preferably reads the detonator serial ID, performs diagnostics, and correlates hole number to detonator serial ID. At this point, the operator can then program the detonator delay time if it has not already been programmed. Once a detonator **20** is connected to the logger, the operator powers up the logger and commands the reading of serial ID, the performing of diagnostics, and, if desired, the writing of a delay time. As the serial ID is read, the logger may assign a sequential hole number and retains a record of the hole number, serial ID, and delay time.

The foregoing sequence can beneficially be accomplished using the above-noted Unknown Detonator Read Back and Single Check Continuity commands and possibly the Program Delay/Scratch command. Preferred details of these commands are set forth below.

Unknown Detonator Read Back

By this command, the blasting machine **40** or logger requests a read back of the serial ID, delay time, scratch information, and status flags (notably including its charge status) of a single, unknown detonator **20**. The bus detection flag is not set by this command. (As an alternate to this command, the logger could instead perform a version of the Auto Bus Detection and Known Detonator Read Back commands described below).

Single Check Continuity

By this command, the logger requests a continuity check of a single detonator **20** of which the serial ID is known. The logger may (preferably) issue this command prior to the programming (or re-programming) of a delay time for the particular detonator **20**. In response to this command, the ASIC **30** of the detonator **20** causes a continuity check to be conducted on the bridgewire **27**. The continuity check can be beneficially accomplished, for example, by the ASIC **30** (at its operating voltage) causing a constant current (e.g., about 27 μ A with a nominally 1.8Ω bridgewire **27** in the embodiment described here) to be passed through the bridgewire **27** via, e.g., a MOSFET switch and measuring the resulting voltage across the bridgewire **27** with, e.g., an A/D element. The overall resistance of the bridgewire **27** can then be calculated from the ohmic drop across the bridgewire **27** and the constant current used. If the calculated resistance is above a range of threshold values (e.g., in the embodiment described here, 30 to 60 $k\Omega$ range), the bridgewire **27** is considered to be open, i.e., not continuous. If such error is detected, then the detonator **20** responds back with a corresponding error code (i.e., continuity check failure as indicated by the respective data bit of the command word).

Program Delay/Scratch

By this command, if the detonator **20** has not already been programmed with a delay time or if a new delay time is desired, the operator can program the detonator **20** accordingly. Through this command, the blasting machine **40** or logger requests a write of the delay and scratch information for a single detonator **20** of which the serial ID is known. This command also preferably sets the bus detection flag (conveyed by the respective data bit of the command word) high.

10 After some or all detonators **20** may have been thus processed by the logger, they are connected to the bus **18**. A number of detonators **20** can be connected depending on the specifics of the system (e.g., up to a thousand or more in the particular embodiment described here).

Enhanced Logger

A special multiple slave logger **50** (shown in FIG. 14) having additional functions may also be used. The multiple slave logger **50** is powered by a set of batteries **56**, and includes an LCD display **55**, an oscillator **52**, and a current limiter **57**. An electrical interface **58** connects the bus line **18** or **18'** (or to an individual leg wire **19** or leads for a detonator **20**) to a line driver and talkback current reader **51** (which transforms talkback current into a voltage the microcontroller can read), controlled by the microcontroller **53**, and an EEPROM **54** stores all detonator data during logging, which data is referred to by the microcontroller **53** when verifying detonators (e.g., on a bus, branch, or row). The maximum current is also limited via the line driver (or a set of two redundant resistors), in case an electric detonator is inadvertently connected to the bus with the multiple slave logger **50** still powered up, or a detonator ignition element is shorted to the bus. The voltage used throughout operation of the multiple slave logger **50** is the logger voltage (preferably, e.g., 6.5V for $V_{L,H}$ of FIG. 6b and 2.0V for $V_{L,L}$ of FIG. 6b), which is limited to below the no-fire capacitive discharge voltage of the detonators' ignition elements, so the blasting area does not need to be cleared of personnel.

The multiple slave logger **50** preferably includes the functions of a logger—and is used—as described above, but includes the additional capability of communicating with multiple detonators over a bus wire, branch, or row. During the process of individual logging as described above, the user preferably assigns the detonators into branches or rows if appropriate by (while logging each detonator) entering those values into the multiple slave logger **50**, which records the respective branch or row information for each detonator. After the detonators are individually logged and connected, the multiple slave logger **50** is successively connected to each row or branch (or just to the bus) and verifies that each of the respective logged detonators (e.g., using the Known Detonator Read Back command described above) are electrically connected and talkback with the proper current (preferably, e.g., approximately 1.0 mA for $I_{L,H}$ of FIG. 7b and 0 mA for $I_{L,L}$ of FIG. 7b). If any logged detonator is not found, appropriate action is then taken to re-check its electrical connection, etc. The multiple slave logger **50** may also preferably be configured to detect and alert the user to the presence of a short and/or an electric detonator (either of which will result in an inappropriately low resistance for the bus, branch, or row), and preferably power down.

Alternately, rather than individually logging detonators, connecting them to the bus, branch, or row, and then using the multiple slave logger **50** to check them, the multiple slave logger **50** may be configured to permit the logging, connecting, and verification steps to be performed together. In this case, the multiple slave logger **50** is connected to a bus,

branch, or row, and a first detonator is connected to the same. The multiple slave logger **50** logs and verifies the first detonator; then a second is connected to the bus, branch, or row, and the multiple slave logger **50** logs and verifies that detonator; then a third is connected, ad infinitum. This method can be employed preferably with the multiple slave logger **50** using an Auto Bus Detection command (described below with reference to the blasting machine), or alternately with an Unknown Detonator Read Back followed by a command to set the bus detection flag high for the detonator once read.

Operation—by Blasting Machine

In any case, the operator next powers up the blasting machine **40**, which could be configured to initiate a check for the presence of incompatible detonators and leakage, and is preferably configured to prompt the user to enter a password to proceed. The logger is then connected to the blasting machine **40** and a command issued to transfer the logged information (i.e., hole number, serial ID, and delay time for all of the logged detonators), and the blasting machine **40** provides a confirmation when this information has been received. (Although used in the preferred embodiment, a logger need not be separately used to log detonators **20**, and a system could be configured in which the blasting machine **40** logs the detonators **20**, e.g., using Auto Bus Detection command or other means are used to convey the pertinent information to the blasting machine **40** and/or conduct any other functions that are typically associated with a logger such as the functions described above).

The blasting machine **40** may be programmed to then require the operator to command a system diagnostic check before proceeding to arming the detonators **20**, or to perform such a check automatically. Such a command will cause the blasting machine **40** to check and perform diagnostics on each of the expected detonators **20**, and report any errors, which must be resolved before firing can occur. The blasting machine **40** and/or ASICs **30** are also preferably programmed so that the operator can also program or change the delay for specific detonators **20** as desired.

The blasting machine **40** and/or ASICs **30** are preferably programmed to permit the operator to arm the detonators **20**, i.e., issue the Charge command (and the ASICs **30** to receive this command) once there are no errors, which causes the charging of the firing capacitors **26**. Similarly, the blasting machine **40** and/or ASICs **30** are preferably programmed to permit the operator to issue the Fire command (and the ASICs **30** to receive this command) once the firing capacitors **26** have been charged and calibrated. The blasting machine **40** and/or ASICs **30** are also preferably programmed so that if the Fire command is not issued within a set period (e.g., 100 s), the firing capacitors **26** are discharged and the operator must restart the sequence if it is wished to perform a firing.

The blasting machine **40** is also preferably programmed so that, upon arming, an arming indicator light(s) lights (e.g., red), and then, upon successful charging of the detonators **20**, that light preferably changes color (e.g., to green) or another one lights to indicate that the system is ready to fire. The blasting machine **40** is also preferably programmed so that the user must hold down separate arming and firing buttons together until firing or else the firing capacitors **26** are discharged and the operator must restart the sequence to perform firing.

The foregoing sequence can be beneficially accomplished with other commands noted above, preferred details of which are discussed below.

Auto Bus Detection

This command permits the blasting machine **40** or multiple slave logger **50** to detect any unknown (i.e., unlogged) detonators **20** that are connected to the bus **18**, forcing such detonators to respond with their serial ID, delay data, scratch data, and current status flag settings. The blasting machine **40** (and multiple slave logger **50**) and ASIC **30** may preferably be configured and programmed so that this command is used as follows:

1. The blasting machine **40** or multiple slave logger **50** broadcasts the Auto Bus Detection command packet on the bus **18**. All detonators **20** receiving the command that have not previously been detected on the bus **18** (as indicated by their respective bus detection status flag settings) calculate a “clock” value that correlates to their serial IDs and/or delay time information, and then enter a wait state. The correlated clock value can, for example, be calculated from an 11-bit number derived from the CRC-8 of the combined serial ID and selected data bits (e.g., 8 bits) of the delay register word of the Auto Bus Detection command packet, so that adequate time is afforded between each possible clock value for the initiation of a response (including any delay as described below) from a corresponding detonator **20**.
2. The blasting machine **40** or multiple slave logger **50** then begins issuing a “clock” sequence on the bus **18** that continues (except when halted or aborted as described below) until it reaches a number that correlates to the highest possible detonator serial ID in the system (for example, using the 11-bit number described above, there may be 2,048 possible clock values). Time must be allowed between the end of the Auto Bus Detection command packet and issuance of a clock that correlates to the first possible serial ID, to permit calculation by the ASICs **30** of the clock values that correlate to their serial IDs. This can be accomplished by including a wait time (e.g., 10 µs in the embodiment described here) between the end of the detection command packet and the leading edge of the first transition of the clock. To enable current talkback (as described elsewhere herein), the bus **18** is preferably held low during this time, but it can alternately be held high.
3. When the clock value for a particular unlogged detonator **20** is reached, the ASIC **30** of that detonator **20** responds. In the embodiment described here, time (during which the bus **18** is held high or low, preferably low) is permitted for the initiation of a response that is delayed by a predetermined period as shown in FIG. 9. The system may preferably be configured so that if the bus **18** is not pulled low before a predetermined timeout period (e.g., 4,096 ms), the detection process will abort.
4. Upon sensing a response from one or more detonators **20**, the blasting machine **40** or multiple slave logger **50** halts the clock sequence and holds the bus (preferably low) until the full response packet is received, at which point the clock sequence resumes. Alternately, adequate time for the transmission of a full packet could be permitted between the counting of each clock value that correlates to a possible serial ID, however, this would be slower. The blasting machine **40** or multiple slave logger **50** records at least the serial ID (and optionally also the device settings) of any responding detonators **20**. If more than one ASIC **30** begins responding simultaneously, the blasting machine **40** or multiple slave logger **50** preferably ignores such responses and preferably resumes the clock sequence as it would otherwise.

13

5. The process starting with the Auto Bus Detection command packet is then repeated using a different delay time or a different dummy serial ID until no unlogged detonators **20** respond (i.e., until a full clock sequence is counted out without any devices responding), at which point it is deemed that all detonators **20** connected to the bus **18** are identified.
6. When the autobus detection sequence is complete, the blasting machine **40** or multiple slave logger **50** then sends (in any desired order such as by serial ID) the Known Detonator Read Back command (described immediately below) to each individual known detonator **20**, i.e., all those that responded to the Auto Bus Detection command, as well as all those that were initially identified to the blasting machine **40** by the logger.

Enhanced Auto Bus Detection

As the number of unidentified detonators connected to a bus or branch line increases, the likelihood increases that two or more will talkback simultaneously in response to a single clock value after an ABD command issued on that line by a blasting machine or enhanced logger. Further, in some cases, step 5 above might not succeed in distinguishing detonators even when repeated with different dummy values. (The probability of this occurring may for example become significant if a large number of unidentified detonators are intentionally connected to a line). The Applicant has developed a novel enhancement to the detection process that addresses this possibility by employing a digital level discrimination process and a “deconvolution” algorithm in order to ascertain the identity of simultaneously responding detonators. Using this enhanced process, the simultaneous talkback from multiple detonators is received by multiple discriminators and the resulting information processed so as to extract out each unique responding serial ID based on known information including the clock value that elicited the multiple responses and the CRC calculation used. This enhancement provides a robustness that, for example, can permit a user to connect an entire array of detonators having specific factory-preset delay times without need for a time-consuming one-by-one manual logging of each detonator.

Referring to FIGS. 15 and 16, an embodiment of an enhanced autobus detection process capable of handling unresolved double-responses is described. If after a number of iterations (e.g., three more) of step 5 above using different dummy values detonators continue responding simultaneously to one or more clock values, the master device will no longer ignore such responses (as per the end of step 4 above) and will instead additionally route them to a second discriminator **61** having a higher ('2') threshold. (As an alternative to the two physically separate discriminators depicted in FIG. 16, both discriminators could reside in the same hardware element, ordinarily controlled by low ('1') threshold software, and controlled by a higher ('2') threshold software when simultaneous responses are re-routed to it). The master device's processor (e.g., microcontroller **53** of the multiple slave logger **50**) then performs, for each individual bit of such responses, a logical OR operation on the data from the first discriminator **60** (i.e., that used, e.g., by talkback current reader **51** of multiple slave logger **50**, for the initial reading of talkback) and from the second discriminator **61**. Any bits (e.g., those in bit positions **2** and **6** on the right side of FIG. 15) of a response ascertained as high by the second discriminator **61** signify high responses from two simultaneously responding detonators, while any bits ascertained as low by the first discriminator **60** conversely signify two low responses. All remaining bits (i.e., those read by the first discriminator **60** as

14

high but read as low by the second discriminator **61**) remain ambiguous, signifying either a high from one detonator and a low from another or vice versa. The respective sources of the high and the low for these ambiguous bits can be resolved, however, using known information including the clock value that elicited the double-response, and the CRC basis and algorithm employed. Specifically, the master device's processor begins calculating the pertinent CRC values for each permutation of possible serial ID (where *n* ambiguous bits yields 2^n candidate serial IDs). Once it identifies a serial ID that produces a CRC value matching the pertinent clock value, that is taken as one of the simultaneously responding unknown detonator's serial ID; the other unknown detonator's serial ID is then ascertained by taking the complement (i.e., 1 replaces 0 and vice versa) of the ambiguous bits of the first serial ID. As an alternative to employing an additional discriminator and algorithm in the master device, the detonator could be configured so that—if remaining unidentified after a first or n^{th} iteration of clock sequences—its digital logic core performs a different calculation on its serial ID (e.g., a different CRC formula, summing all or some of the serial ID's binary or digital values, etc.) and generates another value upon issuance of which in the next clock sequence (that the master device would transmit, preferably limited to the possible values that could be generated by that calculation on the possible serial ID range) the detonator will then respond; if multiple responses still persisted after that, a yet further different calculation could be performed by the detonator and a corresponding clock sequence range issued by the master device, and so on.

Known Detonator Read Back

By this command, the blasting machine **40** or logger requests a read back of a single detonator **20** of which the serial ID is known. In response to this command, the detonator **20** provides its serial ID, delay time, scratch information, and status flags (notably including its charge status). This command preferably sets the bus detection flag high so that the device no longer responds to an Auto Bus Detection command.

Check Continuity

The system should be configured so that this command is required to be issued before the Charge command (described immediately below) can be issued. By this command, the blasting machine **40** broadcasts a request to all detonators **20** connected to the bus **18** to perform a continuity check. In response, each ASIC **30** in the detonators **20** performs a continuity check on the bridgewire **27** such as is described above with respect to the Single Check Continuity command sent to a specific detonator **20**.

Charge

By this command, the blasting machine **40** requests a charge of all detonators **20** connected to the bus **18**. After charging of each detonator **20**, its charge status flag is set high. The detonators **20** respond back to the blasting machine **40** only if an error has occurred (e.g., a CRC error, the bus detection flag is not high, or—if staggered charging as described below is used—the scratch register is set to zero), in which case the response includes the corresponding error code.

If a large number of detonators **20** are connected to the bus **18**, charging may preferably be staggered so that the detonators **20** are each charged at different times such as by the following steps:

1. The blasting machine **40** broadcasts the Charge command on the bus **18**.

2. The blasting machine **40** then begins issuing a clock sequence at a selected temporal frequency on the bus **18**, which sequence continues up to a certain maximum number corresponding to the maximum number of the scratch register, e.g., 4,096.
3. When the number of clocks reaches a number programmed in the scratch register of a particular detonator **20**, that detonator **20** charges. The detonators **20** can have unique scratch values or they can be grouped by scratch number into banks (of e.g., 2 to 100) that thus charge concurrently. The clock frequency should be timed and the detonator scratch values set sequentially in such a way as to ensure that a desired minimum individual (i.e., non-overlapping) charging time is afforded to each detonator **20** or bank of detonators **20**, which can be done in a number of ways (e.g., using scratch numbers of 1, 2, 3 . . . at a given clock frequency has the same effect as scratch numbers of 2, 4, 6 . . . at a clock frequency that is twice as fast). When the clock corresponding to the detonator **20** is received, the ASIC **30** begins charging the firing capacitor **26** (see, e.g., FIG. 5) until the capacitor voltage reaches a predefined charged threshold, at which point charge-topping of the firing capacitor **26** is then maintained.
4. If the capacitor voltage threshold is not achieved within a specified desired window (e.g., in the present embodiment, between 1.048 s and 8.39 s after the ASIC **30** begins charging the firing capacitor **26**), then the ASIC **30** times out and sets the charge status flag to low (but does not need to be programmed to send a response communicating the error at this time, assuming that the Verify Charge command described below is used).
5. The charge process ends when the bus **18** is held low for more than a predetermined timeout period, e.g., 4.096 ms.

The minimum time required to charge a network of detonators in a staggered fashion thus essentially equals the desired individual (or bank) capacitor charging time (which in turn depends on the particular charging process used and the size of the firing capacitor **26**) multiplied by the number of detonators **20** (or banks). For example, in the present embodiment, about 3 s per capacitor may be desirable with a system including 100 detonators or detonator banks in which the constant-current regulation process described below is employed, and results in an overall charging time of 300 s. Alternatively, the charge clocking can be controlled over a wide range of scratch values, e.g., clocking to a certain number of pulses (where all detonators with scratch values up to this pulse number will charge), pausing the clocking momentarily to allow these detonators to adequately charge to full capacity before issuing further clock pulses, pausing and resuming again if desired, and so on.

At the device level, the electricity supplied to each firing capacitor **26** during charging may preferably be through a constant-current, rail-voltage regulated charging process, as is shown in FIG. 12. In such a charging process, the current draw is held constant at a relatively low amount (e.g., at 1 mA) while voltage increases linearly with time until a "rail-voltage" (which is the regulator voltage, which is in turn suitably chosen together with the capacitance of the firing capacitor **26** and the firing energy of the bridgewire **27**) is reached, after which the voltage remains constant at the rail voltage and the current draw thus decreases rapidly. Such charging regulation, which is known for example in the field of laptop computer battery chargers, may be accomplished by several methods such as a current-mirror using two bipolar transistors or

MOSFETs, a fixed gate-source voltage on a JFET or MOSFET, or a current feedback using an op amp or comparator.

It is noted that talkback from the detonators to the blasting machine may alternately be performed with the bus voltage held high (during which the detonators' storage capacitors are continually charged), but the baud rate may need to be limited to permit talkback current to be discriminated adequately from charging current. For example, in a given system at a rate of a few hundred baud, every detonator on the bus may be read reliably and the bus maintained at a logger mode voltage.

Charge Verify

By this command, the blasting machine **40** broadcasts a request to all detonators **20** on the bus **18** to verify that they are charged. If an ASIC **30** did not charge (as reflected by a low charge status flag setting per the charge procedure described above) or has a CRC error, it immediately responds back with the appropriate error code and other information including its status flags. The Charge Verify command can also effectively provide a verification of the proper capacitance of the firing capacitor **26** if a charging window time as described above with reference to the charging process is employed, and its limits are respectively defined to correspond to the time required (using the selected charging process) to charge a firing capacitor **26** having the upper and lower limits of acceptable capacitance. For example, in the embodiment described here, using a constant-current (1 mA), rail-voltage limited charging, a 47 μ F capacitor nominally charges to 25V in 1.2 s, and a window of from 0.5 to 3 s corresponds to acceptable maximum/minimum capacitance limits (i.e., about 20 to 100 μ F), or a 374 μ F capacitor nominally charges to 25V in 9.4 s, and a window of from 6.25 to 12.5 s corresponds to acceptable maximum/minimum capacitance limits (i.e., about 250 to 500 μ F). If the blasting machine **40** receives an error message in response to this command, it can re-broadcast the Charge command and terminate the sequence, or alternately it could be configured and programmed to permit the individual diagnosing and individual charging of any specific detonators **20** responding with errors.

Calibrate

Each one of detonators **20** contains an internal oscillator (see FIG. 5), which is used to control and measure duration of any delays or time periods generated or received by the detonator **20**. The exact oscillator frequency of a given detonator **20** is not known and varies with temperature. In order to obtain repeatable and accurate blast timing, this variation must be compensated for. In the present embodiment this is accomplished by requesting the detonator **20** to measure (in terms of its own oscillator frequency) the duration of a fixed calibration pulse, NOM (preferably, e.g., 0.5 to 5 s in an embodiment such as that described here), which is generated by the blasting machine **40** using its internal oscillator as reference. In the present embodiment, the detonator **20** then uses the measured pulse duration, CC, to compute the firing delay in terms of the oscillator counts using the following formula: counts = DLY * (CC/NOM) where DLY is the value of the delay register. (In the present embodiment it is assumed that the temperature of the detonator **20** has become stable or is changing insignificantly by the time the actual blast is performed).

By the Calibrate command (the address bytes of which may contain any arbitrary data), the blasting machine **40** broadcasts a request to calibrate all detonators **20** on the bus **18**. A detonator **20** responds back to the calibrate command only if an error has occurred (e.g., a CRC error or the bus detection or charge status flags are not high), in which case the response includes the corresponding error code. If there is no

error, immediately after the calibration packet has been received, the detonator **20** waits until the bus **18** is pulled high for a set period (e.g., the same period described above as NOM), at which point the ASIC **30** begins counting at its oscillating frequency until the bus **18** is pulled back low to end the calibration sequence. The number of counts counted out by the ASIC **30** during this set period is then stored in the detonator's calibration register (and is later used by the ASIC **30** to determine countdown values) and the calibration flag is set high. Pulling the bus **18** low ends the Calibrate command sequence, and the rising edge of the next transition to high on the bus **18** is then recognized as the start of a new command.

Calibrate Verify

By this command, the blasting machine **40** broadcasts a request to verify calibration of all detonators **20** on the bus **18**. In response, each detonator **20** checks that the value in its calibration register is within a certain range (e.g., in the embodiment described here, +/-40%) of a value corresponding to the ideal or nominal number of oscillator cycles that would occur during the period NOM. A detonator **20** responds back only if the calibration value is out of range or another error has occurred (e.g., a CRC error or the bus detection, charge, or calibrate status flags are not high), in which case the response includes the corresponding error code.

Fire

By this command, the blasting machine **40** broadcasts a request to fire all detonators **20** on the bus **18**. A detonator **20** responds back to this command only if an error has occurred (e.g., a CRC error, the bus detection, charge, or calibrate status flags are not high, or the delay register is set to zero), in which case the response includes the corresponding error code. Otherwise, in response to this command, the ASIC **30** of each detonator **20** initiates a countdown/fire sequence and sets the fire flag high. The blasting machine **40** and logger and/or ASIC **30** may beneficially be configured and programmed such that this process is as follows (see also FIG. 11):

- Upon receipt of the Fire command, if there are CRC or procedural errors and the ASIC **30** has not yet successfully received a Fire command, then the device answers back immediately with the appropriate error code. (In which case, as shown in FIG. 10d, the blasting machine **40** preferably responds by broadcasting a Discharge command to all detonators **20**; alternately, it could be designed to permit the individual diagnosis and correction of any detonators **20** responding with an error, or it can issue further Fire commands as noted in step 3 below). If there are no errors, then the ASIC **30** enters a "pre-fire countdown," the delay time for which is programmed by delay information of the packet that conveys the Fire command. For example, two bits of a delay register byte can correspond to four different pre-fire countdown delays that are based on the preceding calibration sequence and shifting, e.g., with a value of 1-1 corresponds to a 4.096 s delay, 1-0 to a 2.048 s delay, 0-1 to a 1.024 s delay, and 0-0 to a 0.512 s delay.
- At any time during the counting down of the pre-fire countdown, the detonator **20** can receive a Single Discharge or Discharge command, or another Fire command. If the Fire command is sent again, then the ASIC **30** verifies there are no CRC errors. If there is a CRC error, then the new Fire command is ignored and the existing pre-fire countdown continues to progress. If there are no CRC errors, then the ASIC **30** resets its pre-fire countdown value to the value determined by the

delay register of the new Fire command packet, and starts a new pre-fire countdown based on the new delay value. Depending on the initial pre-fire countdown delay value, it may be possible, and is preferred, to send the Fire command several (in the embodiment described here, three) additional times prior to the expiration of the pre-fire countdown.

- If neither Discharge command is sent before expiration of the pre-fire countdown, the ASIC **30** checks that the bus **18** voltage exceeds a minimum absolute threshold value. If it does not, then the detonator **20** automatically discharges; otherwise, a "final fire countdown" begins and the communication interface of the detonator **20** is preferably disabled so that no further commands can be received. The final fire countdown time is preferably determined based on the calibration described above and a delay value programmed into a delay register in the ASIC **30**. At the conclusion of the countdown of this final fire countdown time, the ASIC **30** causes the firing capacitor **26** to be discharged through bridgewire **27**, resulting in detonation.

It has been found that a system constructed according to the preferred specifics described here, with up to a thousand or more detonators **20** networked to the blasting machine **40**, can reliably provide a timing delay accuracy of better than 80 ppm (e.g., 0.8 ms with 10 s delay).

Discharge

By this command, the blasting machine **40** broadcasts a request to discharge all detonators **20** on the bus **18**. A detonator **20** responds back to this command only if a CRC error has occurred in which case the response includes the corresponding error code (the discharge command is not performed in this case). Otherwise, in response to this command, the ASIC **30** of each detonator **20** stops any fire countdown that may be in progress, and causes the firing capacitor **26** to be discharged.

Discharge Verify

By this command, the blasting machine **40** broadcasts a request to verify the discharging of all detonators **20** on the bus **18**. In response, the ASIC **30** of each detonator **20** verifies that the firing capacitor **26** is discharged, responding back only if a CRC or verification error has occurred (e.g., a CRC error or the bus detection, charge, or calibrate status flags are not high), in which case the response includes the corresponding error code.

Single Discharge

This command is the same as the Discharge command discussed above except that it requires a correct serial ID of a specific detonator **20** on the bus **18**, which detonator responds back with its serial ID, delay and scratch information, status flags, and any error codes.

One of ordinary skill in the art will recognize that even the particular system described here is subject to numerous additions and modifications. For example, not all of the commands described above would necessarily be required, they could be combined, separated, and otherwise modified in many ways, and numerous additional commands could be implemented. As some of many examples, a command could be implemented to clear all bus detection flags of detonators **20** on the bus **18**, to permit resetting of the bus detection process, a command could be implemented to permit individual charge and/or charge verify of selected detonators **20**, etc. Further, other synchronization schemes (e.g., using a third clock line instead of dynamic synchronization) and/or protocols could be used if suitable for a particular application.

Although the present invention has been described in the context of one particular preferred embodiment, one skilled in the art will appreciate that numerous variations, modifications, and other applications are also within the scope of the present invention. For example, the present invention for resolving simultaneous responses can be readily modified for use in conjunction with other detection processes, e.g., a detection process whereby the master device sends out a command to the system conveying the identifying information of all individual devices known to the master device, and where the slave devices are configured and/or programmed so that any slave device the identifying information of which was not included with the command, identifies itself to the master device in response to this command. Further, the present invention may also be employed in numerous master/slave systems other than electronic blasting systems, for example in various military, aerospace, or automotive applications. Thus, the foregoing detailed description of a preferred embodiment is not intended to limit the invention in any way; instead the invention is limited only by the following claims and their legal equivalents.

What is claimed is:

1. For use in an electronic blasting system having a master device and electronic detonators and utilizing a detection process that causes any electronic detonators that have not previously been identified to the master device to identify themselves to the master device, a method for resolving simultaneous responses from multiple electronic detonators comprising the following steps performed by the master device:
  - a. receiving simultaneous responses from multiple electronic detonators with at least two discriminators;
  - b. processing data from said at least two discriminators to resolve said simultaneous responses into known bits and ambiguous bits;
  - c. performing an algorithm to resolve said ambiguous bits; and
  - d. combining the results of steps b and c to ascertain the respective identifications of said simultaneously responding multiple electronic detonators.
2. The method of claim 1, wherein said electronic detonators have factory-preset delay times.
3. The method of claim 1, further comprising the step of said master device sending a verification command on the system based on one or more identifications resolved from step d.
4. The method of claim 1, wherein said simultaneous responses are from no more than two electronic detonators, and said at least two discriminators comprise two discriminators.
5. The method of claim 4, wherein any known bit resolved in step b comprises a high value from both electronic detonators or a low value from both electronic detonators.
6. The method of claim 5, wherein said low values from both electronic detonators are signified by a low reading by a first of said two discriminators and said high values from both electronic detonators are signified by a high reading by a second of said two discriminators.
7. The method of claim 6, wherein said algorithm of step c includes the calculation of possible values corresponding to candidate electronic detonator identifications.

8. The method of claim 7, wherein said possible values comprise CRC values corresponding to candidate electronic detonator identifications.
9. The method of claim 1, wherein said algorithm of step c includes the calculation of possible values corresponding to candidate electronic device identifications.
10. The method of claim 9, further comprising the step of said master device sending a verification command on the system based on one or more identifications resolved from step d.
11. The method of claim 9, wherein said possible values comprise CRC values corresponding to candidate electronic detonator identifications.
12. A master device for use with an electronic blasting system that includes multiple electronic detonators and a detection process that causes any electronic detonators that have not previously been identified to the master device to identify themselves to the master device, the master device being capable of resolving simultaneous responses from at least two electronic detonators and comprising:
  - a. at least two discriminators;
  - b. means for processing data received from said at least two discriminators so as to resolve simultaneous responses from at least two electronic detonators into known bits and ambiguous bits;
  - c. means for performing an algorithm to resolve said ambiguous bits; and
  - d. means for ascertaining, using said known bits and said resolved ambiguous bits, the respective identifications of said at least two simultaneously responding electronic detonators.
13. The master device of claim 12, wherein said simultaneous responses are from no more than two electronic detonators, wherein said at least two discriminators comprise two discriminators, wherein said means for processing data further resolves said known bits into high values received from both electronic detonators and low values received from both electronic detonators, and wherein said low values from both electronic detonators are signified by a low reading by a first of said two discriminators and said high values from both electronic detonators are signified by a high reading by a second of said two discriminators.
14. The master device of claim 13, wherein said means for performing an algorithm calculates possible values corresponding to candidate electronic detonator identifications.
15. The master device of claim 12, wherein said electronic detonators have factory-preset delay times.
16. The master device of claim 15, wherein said master device is a logger.
17. An electronic blasting system having a master device and electronic detonators, comprising:
  - a. means for causing any electronic detonators that have not previously been identified to the master device to identify themselves to the master device; and
  - b. means for resolving any responses received simultaneously by the master device from multiple electronic detonators.
18. The system of claim 17, wherein said electronic detonators have factory-preset delay times.
19. The system of claim 18, wherein said master device is a logger.
